US0D1079850S

(12) **United States Design Patent** (10) **Patent No.:** **US D1,079,850 S**
(45) **Date of Patent:** **** Jun. 17, 2025**

(54) **RING DUMBBELL**

(71) Applicant: **Dong Liu**, Lankao County (CN)

(72) Inventor: **Dong Liu**, Lankao County (CN)

(**) Term: **15 Years**

(21) Appl. No.: **29/982,161**

(22) Filed: **Jan. 5, 2025**

(51) LOC (15) Cl. **21-02**

(52) U.S. Cl.

USPC **D21/682**

(58) **Field of Classification Search**

CLAIM

The ornamental design for a ring dumbbell as shown and described.

DESCRIPTION

FIG. 1 is a perspective view of a ring dumbbell showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
